UNITED STATES PATENT OFFICE.

PETER E. MACDONALD, OF DETROIT, MICHIGAN.

MUSICAL HOOP.

1,259,889.

Specification of Letters Patent. Patented Mar. 19, 1918.

Application filed April 30, 1917. Serial No. 165,329.

To all whom it may concern:

Be it known that I, PETER E. MACDONALD, a citizen of the United States of America, residing at Detroit, in the county of Wayne 5 and State of Michigan, have invented certain new and useful Improvements in Musical Hoops, of which the following is a specification, reference being had therein to the accompanying drawings.

- 10 This invention relates to a musical hoop and the primary object of my invention is to provide a musical hoop or toy which will afford considerable amusement and exercise, to a child, when rolled or driven over a surface, the hoop including musical elements, as bells, that are set in action by the movement of the hoop to produce an effect of tingling or ringing bells of one or more tones.
- 20 Another object of my invention is to provide a tubular metallic hoop which will afford an annular chamber or endless path for musical elements adapted either individually or collectively, by contact with each 25 other or contact with portions of the hoop, to produce harmonious tones.

Another object of my invention is to provide a rollable hoop having chime elements adapted to be successively and intermittently 30 brought into action by the rolling of the hoop to produce harmonious tones.

A still further object of my invention is to provide a hoop for children that is practically indestructible, susceptible to any desired 35 ornamentation, inexpensive to manufacture, and highly efficient as an amusement or exercising device.

The above are a few of the objects attained by the mechanical construction that 40 will be hereinafter described and then claimed, and reference will now be had to the drawing, wherein—

Figure 1 is a vertical longitudinal sectional view of the preferred form of hoop;

45 Fig. 2 is an enlarged cross sectional view of the same;

Fig. 3 is a similar view illustrating a slight modification of my invention;

Fig. 4 is a side elevation of a hoop, partly 50 broken away and partly in section, showing the chimes in connection with the hoop;

Fig. 5 is an enlarged cross sectional view taken on the line $v-v$ of Fig. 4;

Fig. 6 is a plan of the inner side of the 55 hoop, on an enlarged scale, illustrating a

slight modification in connection with the chimes, and

Fig. 7 is a cross sectional view taken on the line VII—VII of Fig. 6.

In the drawing, 1 denotes a hoop that is 60 hollow to provide an endless annular chamber 2 and said hoop is made of tubular material, preferably metal, so as to provide a durable rollable hoop, and so, also to provide walls for the chamber 2 that will be 65 resonant and serve functionally as sounding or sound reflecting surfaces. In using metallic tubing, a piece of tubing may be bent about a former to form the ring or hoop and the ends of the piece of tubing brought together so as to form the endless chamber 2. The ends of the piece of tubing may be 70 welded, brazed or otherwise connected together and thus provide a smooth uninterrupted path or surface within the hoop on 75 which musical elements 3, as bells, may roll or shift when the hoop is in action.

The hoop may be also formed by rolling a piece of skele to simultaneously produce the tubular and ring or hoop form, and 80 furthermore the hoop may be made from metals or a similar material by using dies and formers to impart a tubular shape to the metal.

Irrespective of the method of manufacture, the material is formed to provide a chamber 2 so that it will retain the musical elements 3 therein.

As shown in Figs. 1 and 2, it is preferable to leave an annular slot 4 in the inner 90 wall of the hoop, said slot being formed by the edges of the material. The slot may be of a width as to preclude displacement or loss of the musical elements 3 and at the same time allow sounds to be emitted by the 95 hoop. As shown in Fig. 2, it is essential that the musical elements 3 be of such size as not to pass through the slot 4, and as shown in Fig. 3, small musical elements 5 may be used and the edges of the tube 100 brought very close together so as to form a narrow slot 6.

The musical elements 3 and 5, as indicated above, are preferably in the form of bells, cylindrical or otherwise shaped so 105 that the bells may travel or shift in the chamber 2 during the rolling of the hoop, and by contacting with each other or with walls of the chamber 2, musical tones are emitted from the slot on the hoop. The 110

bells may be of different tones, different sizes and of various materials.

Reference will now be had to Figs. 4 and 5 showing what I term a "chime" hoop. 5 The hoop is similar in construction to the preferred form but the chamber 7 of the hoop is subdivided or partitioned off to provide separate compartments for a chime element 8, and each chime element or group 10 of elements may be confined within a prescribed compartment or space of the chamber 7 by transverse pins 9, rivets or other partitioning means. As an instance of other partitioning means, there are shown 15 in Figs. 6 and 7 inwardly projecting portions 10 of the material forming the hoop. The inwardly projecting portions 10 may be formed by depressing the opposed edges of the material forming the annular slot 11 20 of the hoop thus providing protuberances within the hoop so that the musical elements cannot pass by. In connection with this chime hoop, I reserve the right to provide the hoop with any number of compartments with one or more bells in each compartment so that a desired chime may be attained when rolling the hoop over a surface. The bells or musical elements may 25 also be so confined as to be successively brought into sounding operations, and while 30 in the drawings there are illustrated the preferred embodiments of my invention, it

is to be understood that the structural elements are susceptible to such modifications and variations as fall within the scope of 35 the appended claims.

What I claim is:

1. As a new article of manufacture, a tubular hoop having spherical musical elements therein. 40
2. A hoop having a chamber therein with the outer wall of the chamber constituting the rolling surface of the hoop and the inner wall slotted, and a movable musical element in the chamber of said hoop. 45
3. A hoop having a chamber therein partitioned to provide a plurality of compartments, and a cylindrical bell having a rolling action in each compartment of the chamber hoop. 50
4. A hoop having the periphery thereof formed of tubular material providing an endless chamber, and bells in the chamber of said hoop.
5. A toy having an endless peripheral 55 chamber, and bells in the chamber set in motion and to ringing by movement of the toy.

In testimony whereof I affix my signature in the presence of two witnesses.

PETER E. MACDONALD.

Witnesses:

ANNA M. DORR,
